UNITED STATES PATENT OFFICE.

WILBUR H. CRAFT, OF BUFFALO, NEW YORK.

DESIGN FOR A BADGE.

SPECIFICATION forming part of Design No. 30,644, dated May 2, 1899.

Application filed March 29, 1899. Serial No. 711,020. Term of patent 31 years.

To all whom it may concern:

Be it known that I, WILBUR H. CRAFT, a citizen of the United States, residing in Buffalo, in the county of Erie and State of New York, 5 have invented and produced a new and original Design for Badges, of which the following is a specification, reference being had to the accompanying drawing, showing a part thereof.

The figure of the drawing is a face view of 10 a badge arranged according to my design.

As shown in the drawing, the general outline of my design is a circular disk, upon which is portrayed a rear perspective view of 15 a passenger-train from which a passenger is being ejected by the conductor. Space is afforded above and below the picture for any suitable words and dates.

The design consists in the badge which is disk-shaped in outline, ornamented with an illustration showing the ejection of a passenger from a train. 20

Having thus described my invention, what I claim, and desire to secure by Letters Patent, is—

The design for a badge, as herein shown and 25 described.

In testimony thereof I have signed my name to this specification in the presence of two subscribing witnesses.

WILBUR H. CRAFT.
